LOCK

Norman B. Hurd, Newington, Conn., assignor to
The American Hardware Corporation, New
Britain, Conn., a corporation of Connecticut

Application May 5, 1939, Serial No. 271,873

10 Claims. (Cl. 70—343)

My invention relates to corridor locks, especially useful for hotel guest rooms, steamship staterooms, and the like. The lock is designed to be operated to unlock the door by either one of two different keys, one to be held by the guest occupying the room and which I will term the "guest" key, the other to be held by the chambermaid or room stewart and which I will call the "servant's" key.

10 The object of the present invention is to provide certain new and useful features of construction whereby when the room has been locked by the indoor locking means such as the thumb-turn, the door cannot be unlocked by the servant's key. A "master" key may of course be provided to function at all times with the locks of a plurality of rooms.

In the accompanying drawings—

Fig. 1 is a side elevation of my improved lock, 20 with the cap removed, and showing only such parts of the lock as are necessary to an understanding of my invention;

Fig. 2 is a similar view showing certain parts in 25 a different position and also showing part of the removable cap;

Fig. 3 is a relatively enlarged, vertical cross-section of the upper portion of the lock, said view being taken on the plane of the cylinder axis;

Fig. 4 is a side elevation of a part of the inside 30 of the cap and associated parts.

I have shown and will describe only one preferred form of my invention.

1 is a lock case. 2 is a removable cap. 3 is a spring projected latch-bolt mounted as usual in 35 the face-plate 4. 5 is a knob actuated latch retracting member. This member 5 may be pressed back to retract the latch bolt by means of a knob actuated inside roll-back 6 or by a knob actuated outside roll-back 7. A so-called "night latch" dog 8 is provided for dogging the outside roll-back by pushing in the press button 8' in the face-plate. This dog 8 is released by means of another button 8'' having a walking beam connection 8''' with said dog 8. 9 is a key operated 40 latch retracting bell crank lever pivoted at 9'. The lower end of this lever stands in front of a plate 3' on the tail of the latch-bolt so that when the lever is operated by a key controlled means the latch-bolt 3 may be retracted against the tension of its spring. The upper end of this lever 9 stands in the path of a key controlled roll-back 10 of a cylinder lock. 11 is another lever pivoted intermediate its length on the pivot 9'. 12 is another lever mounted intermediate its length on a 45 pivot 12'. 13 is a link connecting the lower ends

of the levers 11—12. 13' is an arm projecting upwardly from this link, while 9'' is a stud on the side of the lever 9 for engaging the arm 13' at certain times and for the purpose later described. The upper end of the lever 12 is cut back at one side to provide side clearance for the key controlled roll-back 10. The roll-back 10 always moves in a plane coincident with the upper end of the bell crank lever 9. 14 represents the body of the cylinder lock or the like designed to be operated by the usual so-called "flat" key. The roll-back 10 carries on its outer side a slide 15 which in turn carries on its outside a check 15'. Normally this slide is spring repressed so that said check will stand retracted in the position shown in Fig. 1. However, when a long key is introduced into the cylinder lock as shown in Fig. 3, its inclined end will engage the slide 15 and push the check 15' radially outward to the position indicated in Figs. 2, 3 and 4. In the present instance this long key is the "servant's" key. My invention contemplates suitable means to prevent the holder of this key from operating the lock, provided it has been locked by an indoor locking means such as a thumb-turn. 16 is a thumb-turn roll-back hub mounted on the inside of the cap preferably in alignment with the axis of the cylinder lock plug. 17 is a thumb-turn for operating the hub 16. 18 is a roll-back mounted on the hub 16. This roll-back has a slot and standing in the slot is a stud 11' on the upper end of lever 11. Now, assuming the roll-back 18 is rotated from the position shown in Fig. 1 to that shown in Fig. 2, its movement will shift the linkage comprising the parts 11—12—13 from the position shown in Fig. 1 to that shown in Fig. 2, in which position the upper end of the lever 12 will stand in the path of movement of the check 15' so that the servant's key (shown in Fig. 3) cannot turn far enough to reverse the linkage and retract the latch-bolt. The "guest" key, being shorter (see dotted lines, Fig. 3), will not project the check 15' and hence the roll-back 10 may be turned thereby sufficiently to cause the same to engage the upper end of the lever 9 and swing the lower end rearwardly sufficiently to retract the latch-bolt. During this movement the stud 9'' will engage the arm 13' and shift the linkage from the position shown in Fig. 2 to that shown in Fig. 1. It will be noted that when the linkage stands in the undogging position shown in Fig. 1, the end of the link 13 stands close to the rear of the night latch button 8''. Now, if the thumb-turn 17 is operated to shift the linkage to the dogging position shown in Fig. 2, said link 13 will

press the button 8'' outwardly and, through the walking beam connection 8''', will force the dog 8 into position to dog the outside knob roll-back 7. Thus, under such conditions the outer knob is 5 dogged so that the room cannot be entered by turning the outside knob. If the door is closed and locked in this manner, the guest key (or master key) may be used to operate the linkage and retract the latch-bolt while still leaving the 10 outside knob dogged until released by pressing in the night latch button 8''. If, however, the guest wishes to leave the room and wishes to deny the servant entrance in his absence, all he needs to do is to dog the outer knob roll-back 7 by means 15 of the thumb-turn 17 which will throw the linkage to the position shown in Fig. 2, wherein the servant's key will be ineffective. Unless it is desired to exclude the servant the guest would lock his door by simply pressing in the button 8' in the 20 face-plate of the lock.

Operation: Assuming the lock is used on a hotel bedroom door or a stateroom door and that the dogging mechanism is "off," the room may be 25 freely entered and left by simply operating the usual outside and indoor knobs, respectively. Assuming the guest leaves his room and wishes to leave it locked, he simply throws "on" the night latch dog 8 for the outer knob. The room may now be entered by the use of either the guest key 30 or the servant's key, since at such time the dog 12 will be in its "off" position. It should be observed that the operation of either of these keys under this condition will not disturb the position of the dog 8 for locking the outer knob. If 35 the dog 8 is "off" and the room is occupied, the occupant may lock the door by means of the inside thumb-turn 17. This will not only have the effect of throwing the night latch dog 8 to the "on" position locking the outer knob, but it will also throw the dog 12 into its blocking position to prevent latch retraction by means of the servant's key, thereby insuring the occupant of 40 privacy.

I have described my invention in its preferred 45 form but I fully realize that certain modifications and changes may be made without departing from the spirit or scope of the invention by slight changes in design or the substitution of known equivalents for various parts.

50 What I claim is:

1. In a door lock of the character described, a 55 spring-projected latch-bolt, independent roll-backs for inside and outside knob actuation for retracting the latch-bolt, a night latch dog for the outside roll-back, a key actuated roll-back, with means operable thereby to retract said latch-bolt by either of two differently shaped keys, a second dogging device operable from the indoor side of the lock to block at will the retraction of said latch-bolt by one of said keys 60 when said device is in one position, and a check movably mounted on said key actuated roll-back and movable by the last mentioned key into position to be blocked by said second dogging device.

65 2. In a door lock of the character described, a spring-projected latch-bolt, independent roll-backs for inside and outside knob actuation for retracting the latch-bolt, a night latch dog for the outside roll-back, a key actuated roll-back, with means operable thereby to retract said latch-bolt by either of two differently shaped keys, a second dogging device operable from the indoor side of the lock to block at will the re- 70 traction of said latch-bolt by one of said keys 75

when said device is in one position, a check movably mounted on said key actuated roll-back and movable by the last mentioned key into position to be blocked by said second dogging device, said second dogging means coacting with the night latch dog for the outer knob to move the same to the "on" position when the dog for said key actuated roll-back is moved to the "on" position. 5

3. In a lock of the character described, a spring projected latch-bolt, two latch retracting 10 roll-backs for independent operation by inside and outside knobs respectively, a night latch dog for the roll-back for the outer knob only, a key operated mechanism including a roll-back for retracting the latch-bolt from the outdoor side by 15 either of two differently shaped keys, with means operable from the indoor side of the lock to block retraction of the latch-bolt by one of said keys when the outside knob roll-back has been dogged, said means including a device co-acting with the 20 night latch dog to throw it "on" simultaneously with the dogging of the key operated roll-back.

4. In a door lock of the character described, a spring projected latch-bolt, two independent 25 latch retracting roll-backs for operation by inside and outside knobs respectively, a night latch dog for the outside roll-back, a key actuated roll-back, with means operable thereby to retract said latch by either of two differently shaped keys, one being longer than the other, an inside 30 manually operable device movable to a position to block the retraction of the latch-bolt by said key controlled roll-back, a checking device carried by said roll-back and movable by the longer key into position to be stopped by the blocking 35 means when said roll-back is turned and before it has moved sufficiently far to retract said latch.

5. In a lock of the character described, a spring projected latch-bolt, a key operated means for retracting said latch-bolt and comprising a 40 cylinder lock for the outdoor side, a roll-back carried thereby and bearing a movable checking device thereon normally standing in a non-checking position, said cylinder lock roll-back being operable by two differently shaped keys, said 45 checking device on said roll-back being unaffected by the use of one of said keys but being shifted to its checking position by the use of the other key, a manually controlled dogging mechanism operable from the indoor side of the lock 50 to move said dogging mechanism into the path of movement of said checking device to stop the movement of said cylinder roll-back when operated by the last mentioned key before said roll-back has reached the latch-bolt retracting position. 55

6. In a lock of the character described, a spring projected latch-bolt, a key operated means for retracting said latch-bolt and comprising a cylinder lock for the outdoor side, a roll-back 60 carried thereby and bearing a movable checking device thereon normally standing in a non-checking position, said cylinder lock roll-back being operable by two differently shaped keys, said checking device on said roll-back being unaffected by the use of one of said keys but being 65 shifted to its checking position by the use of the other key, a manually controlled dogging mechanism operable from the indoor side of the lock to move said dogging mechanism into the path of movement of said checking device to stop the movement of said cylinder roll-back when 70 operated by the last mentioned key before said roll-back has reached the latch-bolt retracting position, with other roll-back mechanism to permit said latch-bolt to be retracted from either 75

the outdoor or indoor side of the lock and with a night latch dogging means to prevent at will the retraction of the latch-bolt from the outdoor side excepting by said cylinder roll-back.

- 5 7. In a lock of the character described, a spring projected latch-bolt, a key operated means for retracting said latch-bolt and comprising a cylinder lock for the outdoor side, a roll-back carried thereby and bearing a movable checking device thereon normally standing in a non-checking position, said cylinder lock roll-back being operable by two differently shaped keys, said checking device on said roll-back being unaffected by the use of one of said keys but being 10 shifted to its checking position by the use of the other key, a manually controlled dogging mechanism operable from the indoor side of the lock to move said dogging mechanism into the path of movement of said checking device to stop the 15 movement of said cylinder roll-back when operated by the last mentioned key before said roll-back has reached the latch-bolt retracting position, with other roll-back mechanism to permit said latch-bolt to be retracted from either the 20 outdoor or indoor side of the lock and with a night latch dogging means to prevent at will the retraction of the latch bolt from the outdoor side excepting by said cylinder roll-back, said last mentioned night latch dogging means 25 being thrown to its "on" position simultaneously with the throwing "on" of the dogging mechanism to block the key operated roll-back.
8. In a door lock of the character described, a case having a face-plate, a spring projected latch-bolt, independent roll-backs for inside and 30 outside manual actuation for retracting the latch-bolt, a dog to block the turning of the outside roll-back, with means in the face-plate to
- 35

operate said dog, a key actuated roll-back, with means operable thereby to retract said latch-bolt under such conditions from the outside of the door by either of two differently shaped keys, and a second means operable from the indoor side of the lock for throwing "on" said dog to block the retraction of said latch-bolt by one of said keys, said first mentioned means cooperating with said second means to throw "off" said dog.

9. In a lock of the character described, a lock case having a face-plate, a spring projected latch-bolt, two latch retracting roll-backs for independent operation by inside and outside knobs respectively, a night latch dog for the roll-back for the outer knob only with means accessible in the face-plate to operate said dog, a key operated mechanism including a roll-back for retracting the latch-bolt from the outdoor side by either of two differently shaped keys, with a second means operable from the indoor side of the lock to dog the outside knob roll-back and to also block retraction of the latch-bolt by one of said keys when the outside knob roll-back has been dogged by said second means.
10. In a door lock, a case having a face-plate, a spring latch-bolt projecting through said face-plate, separate roll-backs for retracting said latch from the indoor or outdoor side of said lock, a dog for the roll-back for outdoor latch retraction, means operable in the face-plate for dogging or freeing said roll-back, key operated mechanism for retracting said latch from the outdoor side, and a second means operable at the indoor side of the lock and coacting with the first-mentioned dogging means for moving the same into dogging position and at the same time blocking the retraction of said latch-bolt by one of said keys.

NORMAN B. HURD.
